CHARLES A. FISHER, OF GENESEO, ILLINOIS.

Letters Patent No. 73,177, dated January 7, 1868.

IMPROVEMENT IN HAY-KNIFE.

The Schedule referred to in these Letters Patent and making part of the same.

TO ALL WHOM IT MAY CONCERN:

Be it known that I, CHARLES A. FISHER, of Geneseo, in the county of Henry, and State of Illinois, have invented a new and improved Hay-Knife; and I do hereby declare that the following is a full, clear, and exact description thereof, which will enable others skilled in the art to make and use the same, reference being had to the accompanying drawings, forming part of this specification.

This invention relates to a new and improved method of constructing or shaping knives for cutting hay, whereby the same are rendered more convenient in handling and more effective in operation than hay-knives have hitherto been; and the invention consists in the peculiar form or shape of the knife, and in the handles thereof, as will be hereinafter described.

Figure 1 is a longitudinal side view of a hay-knife formed or constructed according to my invention.

Figure 2 is an edge view of the same.

Similar letters of reference indicate corresponding parts.

As will be noticed in the drawing, this hay-knife is designed to be used with both hands grasping separate handles, and that, while the drawing stroke of the old knife is preserved, the weight of the operator is brought more directly on the knife, and the knife thereby made much more useful or effective. The labor in operating this knife is much less fatiguing than with the old kind, as in the latter case the operator depends principally upon his muscle, in the former case upon his weight.

Referring to the drawings, fig. 1 represents the cutting-edge or blade of the knife, which stands at an angle of about forty-five degrees with the shaft. B is the shaft, and C D are branches of the plate connecting the shaft with the blade of the knife. The shaft, blade, and knife are all cut from a plate of rolled metal, and may be provided with the opening E, or made solid. F represents a handle, which is secured to the shaft by a shank, and stands at a right angle with it, as seen. G is the handle at the top of the shaft, which is secured as the handles of shovels and many other implements are.

As will be seen, the blade is straight on its edge, and consequently can easily be kept sharp. It will be also seen that the shaft is somewhat curved, as seen in fig. 2, at H. This curve allows the weight, which is thrown on to the handle F, to bear more directly on the knife.

I am aware that hay-knives have heretofore been made with inclined cutting-edges, but, as this forms no part of my invention, I do not therefore claim it; but having thus described my invention,

What I claim as new, and desire to secure by Letters Patent, is—

As a new article of manufacture, the hay-knife, when formed from a piece of metal, as shown and described, and provided with the handles F G, as herein set forth.

The above specification of my invention signed by me, this thirteenth day of September, 1867.

CHARLES A. FISHER.
